(57) **CLAIM**

The ornamental design for a wrench, as shown and described.

DESCRIPTION

FIG. 1 is a front perspective view of a wrench according to our new design;

FIG. 2 is a rear perspective view of the wrench of FIG. 1; FIG. 3 is a front elevational view of the wrench of FIG. 1; FIG. 4 is a rear elevational view of the wrench of FIG. 1; FIG. 5 is a top plan view of the wrench of FIG. 1; FIG. 6 is a bottom plan view of the wrench of FIG. 1; FIG. 7 is a right side elevational view of the wrench of FIG. 1; and,

FIG. 8 is a left side elevational view of the wrench of FIG. 1.

The subject matter shown in broken lines is hereby disclaimed and forms no part of the claimed invention.
